FASTENER APPLYING IMPLEMENT

John F. Cavanagh, Providence, R. I., assignor to
 Boston Wire Stitcher Company, Warwick, R. I.,
 a corporation of Maine

Application November 11, 1936, Serial No. 110,364

19 Claims.

(Cl. 1—49)

This invention relates to improvements in fastener-applying devices adapted for attaching papers and other sheets, securing tags and labels to articles of commerce, and for use generally in fastening or stitching together various objects and articles.

One object of the invention is to provide a device of the type indicated for bending the legs of a fastener or staple outwardly in a plane parallel to its crossbar to form a flat pin-stitch.

Another object of the invention is to provide a device of the type indicated for holding the work suspended while the fastener or staple is driven therethrough and thereafter bending the legs of the fastener outwardly at points adjacent the work to substantially align them with the crossbar of the staple to form a flat pin-stitch which may be removed without damage to the work.

Another object of the invention is to provide a device of the type indicated embodying a work-support operated automatically to move the work against the fastener-applying means to grip and hold it away from the clinching anvil while a staple is being driven through the work.

Another object of the invention is to provide a device of the type indicated in which the work-support and fastener-applying mechanism are operated in succession by a common means to grip and hold the work while a staple is being driven.

Still another object of the invention is to provide a device of the type indicated which is simple and compact in structure, efficient and positive in action for performing its intended function, and including novel features in the construction and arrangement of its elements.

Further objects of the improvement are set forth in the following specification which describes a preferred embodiment of the invention, by way of example, as illustrated by the accompanying drawings. In the drawings:

Fig. 1 is a side elevation of a fastener-applying or stapling implement incorporating the novel features of the present invention;

Fig. 2 is a front elevational view of the implement illustrated in Fig. 1;

Fig. 3 is a top plan view of the forward end of the fastener-applying mechanism showing the construction of the actuating lever for the staple-driver;

Fig. 4 is a transverse sectional view on line 4—4 of Fig. 1 showing the pivotal mounting for the fastener-applying arm and staple-magazine and the relationship of certain of the parts of the device;

Fig. 5 is a transverse sectional view of the fas-

tener-applying arm on line 5—5 of Fig. 1 showing the construction of the magazine for holding a supply of fasteners or staples and the pusher for advancing them in the magazine;

Fig. 6 is a longitudinal sectional view on line 6—6 of Fig. 1 showing the construction of the fastener-applying arm at its forward end and the gate for closing the end of the magazine and forming a chute or throat through which the staples are driven;

Fig. 7 is a longitudinal sectional view of the implement showing the work suspended and gripped between the fastener-applying means and the work-support prior to the driving of a fastener;

Fig. 8 is a view similar to Fig. 7 showing the relationship of the parts of the device at the completion of a staple-driving operation while the work is held away from the anvil;

Fig. 9 is a view similar to Fig. 7 showing the fastener-applying mechanism moved toward the anvil to bend the legs of the fastener or staple to form a stitch;

Fig. 10 is a transverse sectional view on line 10—10 of Fig. 7 showing the relationship of the fastener-applying means and work-support at the beginning of a staple-driving operation;

Fig. 11 is a transverse sectional view on line 11—11 of Fig. 8 showing the relationship of the fastener-applying means and anvil after the fastener or staple has been driven;

Fig. 12 is a transverse sectional view on line 12—12 of Fig. 9 showing the legs of the fastener or staple bent by the anvil to form a flat stitch; and

Fig. 13 is a longitudinal sectional view of the forward end of the fastener-applying mechanism showing the relationship of its parts when the gate is opened to permit the magazine to be loaded with a supply of staples.

In its preferred form as herein illustrated the invention is embodied in a fastener-applying implement having stapling mechanism enclosed in a two-part casing of suitable size and shape to fit within the pocket and to be conveniently grasped in the hand. As shown in Figs. 1 and 2 of the drawings the casing 2 is relatively flat and thin, resembling a cigarette case, with its two parts 3 and 4 pivotally connected by a pin or stud 5 and telescopically arranged to adapt them to slide one within the other to operate the fastener-applying means.

The main part 3 of the casing 2 is of generally rectangular shape in outline having opposite lateral walls 7 joined at their edges by integral

flanges or strips 8 and 9. The forward end of the casing section 3 is open and its side walls 7 are cut away at the front to provide rectangular openings indicated at 14. The side walls 7 are also cut away at the bottom to form a rearwardly-extending opening 15 with a portion of the walls and the bottom flange 9 projecting forwardly at 16. Positioned between the side walls 7 and seated on the bottom flange 9 is a bar or strip 17 constituting an anvil, its forward end being flared laterally and formed on its upper face with grooves 18 which extend outwardly toward the sides of the anvil and are shaped as shown in Figs. 1, 2 and 10 of the drawings. Between the opposite grooves 18 the anvil has a rectangular recess or slot 19, see Fig. 7, the bottom wall of which is inclined upwardly from front to rear for a purpose later explained. The rearward end of the bar or anvil 17 is formed with a loop 20 which depends through an opening 21 between the flanges 8 and 9 of the casing section 3. A ring-shaped finger-grip 22, preferably constructed of hard rubber or the like, is suitably secured within the loop 20 to adapt the operator's finger to be inserted therethrough to facilitate handling and operating the implement. The anvil 17 is riveted to the end and bottom flanges 8 and 9 of the casing section 3, as indicated at 23, to secure it in position beneath the staple-applying mechanism to be later described.

The upper portions of the side walls 7 of the main section 3 of the casing 2 are cut away obliquely at 24 and the section 4 of the casing is shaped to fit within the opening thus formed with its top and rearward flanges completing the rectangular outline. In other words, the telescopic section 4 of the casing is of substantially triangular form and of narrower width than the section 3 to provide an overlapping arrangement of the walls of the two parts. At its forward end the side walls of the casing section 4 are pivoted on the pin 5 which may be fastened in the lateral walls 7 of the main section 3 in any suitable manner. As illustrated in Fig. 2, the pivot-pin 5 is in the form of a hollow bolt having a head at one end and a tapped hole at its opposite end for receiving a screw 25 with the heads of the bolt and screw engaging the opposite side walls 7 of the casing section 3. The edges of the side walls of the section 4 are inclined downwardly below the pivot-pin 5 and merge into a forward wall or flange 10 continued across the top and rear of the section to form a comparatively rigid structure which serves as the operating lever for the implement.

As before indicated, the fastener-applying means of the implement as herein shown take the form of stapling mechanism for inserting substantially U-shaped wire staples through the work and bending their legs outwardly against the under side thereof; but it is to be understood that the mechanism of the device may be modified to apply fasteners of different types without departing from the spirit or scope of the invention. As herein shown the stapling mechanism is carried on a pivoted member 30, termed for convenience of description the "stapling arm", which is also constituted as a magazine for holding a supply of the staples. The stapling arm 30 constituting the magazine is preferably of hollow or skeleton construction comprising an outer channel-shaped member 31, see Fig. 5, having a flat bottom 32, upstanding sides 33, and inturned flanges 34 extending along the top of the sides. Enclosed within the channel-shaped

member 31 is a correspondingly-shaped core-member 35 having its bottom secured to the bottom 32 of the member 31 as by spot welding, riveting or the like. The sides of the inner core 35 are positioned inwardly from the sides 33 of the main channel-member 31 to provide space for the legs of the staples S which are straddled across the top of the core. In this way the staple-core 35 is adapted to serve as a track or guide for supporting a series of staples straddled thereacross in position to be successively fed to the driving means. As shown most clearly in Figs. 5 and 6, the top flanges of the inner core 35 are spaced a distance apart along the greater portion of the core but at its forward end they are extended thereacross with their edges meeting to form an arched bridge 36 having its sides lying in oppositely inclined planes to adapt it to support crowned staples of the form shown in Fig. 11 of the drawings. The staples S as herein illustrated have opposite parallel legs 1 joined by an upper head or crossbar 2 which is arched at the center by oppositely inclined angular portions. This latter form of staple has certain important advantages as set forth in U. S. Letters Patent No. 2,052,553, dated September 1, 1936.

The stapling arm 30 is positioned between the sides 7 of the main casing section 3 extending longitudinally thereof above the anvil 17. Its rearward end is pivoted on a cross-pin 37 in the form of a bolt projecting through holes in the side walls 7 of the casing section 3 and in rearward extensions 38 of the side walls 33 of the arm, the bolt being secured in position by a nut 39, see Figs. 1 and 4. At its forward end the stapling arm 30 is provided with an upright head portion 40 in which the staple-driver and other parts of the stapling mechanism are housed. The head 40 is constituted by two parallel side walls or wings 41 formed integral with the lateral walls 33 of the channel-member 31 of the arm 30 and projecting upwardly above the top of the latter, see Figs. 10 and 13. The side walls 33 of the member 31 extend forwardly beyond its bottom wall 32, the core 35 and the wings 41, as shown most clearly in Fig. 6, and the extended ends are bent inwardly to form lateral guides 42 for the legs of the staples, see also Fig. 13. The opposite wings 41 have elongated slots 44 adjacent their upper ends through which extends a pivot-pin 45 for mounting a gate 46 arranged to close against the forward end of the stapling arm 30.

The gate 46 is of substantially box-formation comprising a front wall 47 adapted to seat against the ends 42 of the forwardly-projected walls 33 of the channel-member 31 and having side walls 48 which straddle the sides 33 of said member. Referring to Fig. 1 of the drawings it will be observed that the rectangular openings 14 in the side walls 7 of the casing member 3 provide a clearance space for the sides 48 of the gate 46. The lower ends of the side walls 48 of the gate 46 have notches 49 formed therein for cooperation with lugs 50 protruding from the side walls 33 of the channel-member 31 to latch the gate closed. The gate 46 may be opened or closed by lifting it so that its notches 49 clear the lugs 50, and then rocking it about its pivot-pin 45, the elongated slots 44 in the wings 41 permitting the pivot-pin 45 to move vertically during this operation. The gate 46 is resiliently held in its closed position by a leaf-spring 51 anchored to the top of a lever 52, to be later described, with its forward end bearing against the top of the pivot-pin 45 and engaging in a recessed groove formed in the pin. 75

The spring 51 thus serves to retain the pivot-pin against axial displacement. To facilitate the operation of opening and closing the gate 46 its side walls 48 are formed with circular protuberances 52, see Fig. 2, which may be grasped between the forefinger and thumb. When the gate 46 is closed its forward wall 47 cooperates with the inwardly-bent ends 42 of the forwardly-projecting side walls 33 of the member 31 to form a chute 10 or throat 53 through which the staples are driven, see Fig. 6.

As the staples S are fed off from the end of the core 35 they are driven down through the work by means of a reciprocable staple-driver 60. The staple-driver 60 is constructed in the form of a flat plate or blade of suitable dimensions to adapt it to slide freely between the forward edges of the wings 41 of the stapling arm 30 and the front wall 47 of the gate 46 and to be guided at its lateral edges by the ends 42 of the forwardly-extended and inwardly-bent side walls 33 of the stapling arm 30 and the side walls 48 of the gate, see Figs. 9 and 10. The staple-driver 60 is reciprocated in the head by means of a rockable lever 61 of bifurcated form pivoted to the rearward end of the stapling arm 30 between upwardly-directed ears 62 on the extensions 38 of the stapling arm. The lever 61 is comprised of a pair of spaced-apart rails 63 which abut the inner faces of the upstanding ears 62 and are pivoted thereto by a pin 64 extending between the ears. The rails 63 extend forwardly through notches or slots 65, see Fig. 2, in the opposite side edges of the staple-driver 60 and the forward ends of the rails are curved to form hooks 66 for holding the staple-driver from displacement when the gate 46 is open. The rails 63 are held in their spaced-apart relationship by integral U-shaped flanges 67, see Figs. 3 and 7, folded inwardly and then upwardly with their sides abutting in contiguous relationship and soldered, welded or otherwise secured together to form a rigid structure. As herein illustrated the flanges 67 are in the form of loops to provide lateral bridge-ports spaced apart longitudinally of the lever 61 and extended upwardly with the outer edges of their looped portions shaped to provide a cam-face 68 for a purpose to be later described.

The lever 61 is yieldingly held in normally raised position with respect to the stapling arm 30 by the spring 51 which bears against the pivot-pin 45 to hold the gate 46 closed. As illustrated in Figs. 3 and 7, the spring 51 extends rearwardly from its curved end overlying the pivot-pin 45 with its opposite end held under the forward inwardly-folded bridge-portion of the loop-shaped flanges 67. At its rearward end the spring 51 is provided with laterally-extending ears 70 which overlie the upper edges of the opposite rails 63 of the lever 61 to thereby hold the spring under tension. Upward movement of the lever 61 with respect to the stapling arm 30 is limited by the engagement of the rails 63 with outwardly-bent lugs 71 on the wings 41, see Figs. 1 and 13. The stapling arm 30 and lever 61 carried thereon are yieldingly rocked upwardly as a unit about the pivot-pin 37 to the inoperative position illustrated in Fig. 1 by a spring 72 connected between an inwardly-bent lug 69 on one of the rails 63 and a hook 73 at the forward upper end of the casing section 4. As illustrated in Fig. 7, the hook 73 is provided on the inwardly-bent end of one leg of a bifurcated bracket 74 which fits within the channel formed by the side walls and connecting flange of the casing section 4 at its forward end,

the bracket being secured in place by a rivet 75. Upward movement of the stapling arm 30 is limited by the engagement of the upper edges of the wings 41 with a stop 76 bent inwardly from the lower edge of the crosspiece or web of the bracket 74.

The staples are slid forwardly on the core 35 by a follower or staple-pusher 78 to progressively feed them into position to be driven by the driver 60. As shown in Figs. 5 and 13, the staple-pusher 78 is of usual form, being preferably constructed of sheet-metal with an arched top conforming to the top of the core 35 and lateral leg portions 79 straddling the sides of the core. The staple-pusher 78 is urged forwardly on the core 35 by means of an elastic cord 80 connected at one end to an upstanding ear 81 at the rear of the pusher. The cord 80 extends forwardly from the pusher 78 around a guide 82 between the wings 41 of the stapling arm 30 and then rearwardly with its opposite end connected by a hook 77 to the pin 64 which pivotally mounts the lever 61. The staple-pusher 78 is provided with a centrally positioned upstanding ear 83 at its forward end, see Fig. 1, for engaging the staple-driver 60 to prevent the pusher from moving into the staple-throat 53 when the staples are exhausted. Laterally-extending ears 84 at the rearward end of the pusher 78, see Fig. 5, are adapted to engage the rearward edges of the wings 41 to prevent it from moving out of the magazine when the gate 46 is opened and the staple-driver released.

A staple-retainer 85 positioned above the forward end of the core 35 acts to prevent the staples S from being ejected from the magazine by the pusher 78 when the gate 46 is opened. The staple-retainer 85, shown most clearly in Fig. 13, is preferably constructed in the form of a sheet-metal U-shaped member positioned between the opposite wings 41 and pivotally mounted on a pin 86 extending therebetween. The lower edge of one leg of the U-shaped member 85, located at one side of the ear 83 on the pusher 78, is of arcuate shape to form an eccentric cam-face 87 which is adapted to engage the staples with a dogging action to restrain them from ejection from the magazine when the gate 46 is opened. A spring 88 coiled around the pin 86 and held at one end under a finger 89 on one of the wings 41 is arranged with its opposite end engaging the crosspiece or web 90 of the retainer 85 whereby it acts to rock the latter to wedge its cam-face 87 into engagement with the staples when the gate 46 is opened and the staple-driver 60 released. When the gate 46 is closed the staple-retainer 85 is automatically rocked to inoperative position as illustrated in Fig. 8 by the staple-driver 60 which engages the crosspiece or web 90, see also Fig. 13.

In accordance with the present invention a work-support 91 is provided for cooperation with the stapling mechanism to grip and hold the work away from the anvil 17 while a staple is being driven therethrough. The work-support 91 is in the form of a rectangular bar of resilient material extending longitudinally of the implement below the stapling arm 30 and pivotally mounted intermediate its ends on the bolt 31. As illustrated in Figs. 1 and 4, the bar or work-support 91 is provided with upstanding ears 92 which abut the inside faces of the rearward extensions 38 of the member 31 and are formed with apertures through which the cross-pin or stud 37 extends. The forward end of the work-support 91 is bent downwardly so that it normally lies in the recess or slot 19 in the anvil 17 with its upper face 75

flush with the upper face of the anvil. The opposite or rearward end of the work-support 91 is bent upwardly in an arm 93 curved generally in an arc and terminating in a reversely curved portion 94. A leaf-spring 95 attached to the work-support 91 by a rivet 96 or other means and engaging a cross-pin 97 extending between the sides of the casing section 3 normally tends to rock the work-support to yieldingly maintain its forward end in the recess 19 as illustrated in Fig. 1.

The work-support 91 is operated in particular timed sequence with the staple-driver 60 to cause the work W to be gripped and held away from the anvil 17 before a staple S is driven. The forward end of the work-support 91 is raised by the action of a roller 98 carried by the casing section or lever 4 and engaging the curved arm 93 of the support. The roller 98 is rotatably mounted on a stud 99 extending between the side walls of the casing section 4 and secured therein by riveting over its ends, or in any other suitable manner. The roller 98 and the arm 93 on the work-support 91 are so arranged and related that normally the roller is positioned above and closely adjacent the rearwardly curved portion 94 of the arm when the casing section 4 is in its raised position. A second roller 100 is similarly mounted within the casing section 4 and positioned forwardly of the roller 98 to overlie the arched flanges 67 on the lever 61 to adapt it to engage the cam-face 68 on their upper edges. The implement having now been described in detail its mode of operation will be next explained.

The operator inserts one finger through the handgrip 22 and grasps the implement with the palm of the hand resting against the top of the casing section 4 and the thumb and fingers straddling its sides. The papers or other articles to be attached are placed in the opening between the anvil 17 and the stapling arm 30 and pressure is then brought to bear upon the upper edge of the casing section 4 by squeezing the fingers against the bottom of the lower section 3. Under this action the casing section 4 is telescoped within the section 3 with a sliding action as the parts pivot on the pin 5.

As the casing section 4 is depressed the roller 98 immediately engages the curved end 94 of the arm 93 to rock the work-support 91 about its pivot 37 to raise its forward end from the position shown in Fig. 1 to that shown in Fig. 7 whereby to clamp the work W against the under side of the stapling arm 30. Concurrently therewith the roller 100 on the casing section 4 is caused to roll on the cam-face 68 on the actuating lever 61 whereby the latter and the stapling arm 30, which is resiliently held in spaced relation thereto by the spring 51, are rocked downwardly as a unit toward the anvil 17. Due to the relatively short leverage of the arm 93 the forward end of the work-support 91 moves upwardly faster than the forward end of the stapling arm 30 swings downwardly, and the two parts continue to move toward each other until they engage and grip the work W therebetween, see Figs. 7 and 10. The work-support 91 continues to be rocked on its pivot 37 until the arcuate portion of the arm 93 is concentric with the arc of movement of the roller 98 about the pivot 5, the roller 98 thereafter rolling on the arm 93 and holding the forward end of the work-support raised and the work suspended thereon.

It has been stated that the work-support 91 is constructed of resilient material and due to its

ability to yield provision is made for variations in the thickness of the work. As the work-support 91 offers greater resistance to yielding than the spring 51, continued movement of the casing section 4 acts to rock the lever 61 downwardly about its pivot-pin 64 toward the stapling arm 30. The forward end of the lever 61 being engaged with the staple-driver 60 the movement of the lever causes the driver to be actuated through a driving stroke. A staple S advanced along the core 35 of the stapling or magazine arm 30 into the throat 53 by the staple-pusher 78 is engaged by the lower edge of the staple-driver 60 and driven through the work as it is held suspended above the anvil 17 in the manner illustrated in Figs. 8 and 11. As the staple S is thus driven through the work its legs are guided and held against lateral distortion by the terminal edges of the inwardly-bent ends 42 of the side walls 33 of the stapling arm 30.

After the staple S has been driven through the work continued application of the pressure on the casing sections 3 and 4 causes the work-support 91 to yield so that the stapling arm 30 will be rocked downwardly toward the anvil 17. As the stapling arm 30 moves toward the anvil 17 the forward end of the work-support 91 enters the slot 19 therein and the ends of the staple legs engage the slots or grooves 18 in the anvil which act to spread them outwardly away from each other as indicated in Figs. 11 and 12. Instead of the legs 1 of the staple S being curled or bent upwardly to form a clinch they are bent sharply at points adjacent the under side of the work and extended outwardly in a plane coincident with the under side of the work. As a result, the bent legs extend parallel to the crossbar of the staple to form a flat pin-stitch which may be readily withdrawn by bending or slightly folding the work and pushing out the staple.

After each stapling operation the casing sections 3 and 4 are released and automatically returned to their inoperative position. The spring 72 connected between the lever 61 and the bracket 74 on the casing section 4 rocks the stapling arm 30 about its pivot 37 to the position shown in Fig. 8, which movement is augmented by the tensioned staple-support 91. Meanwhile, the spring 51 rocks the lever 61 with respect to the stapling arm 30 to the position illustrated in Fig. 7, the upward movement of the lever 61 being limited by the engagement of its rails 63 with the outwardly-directed lugs 71 on the wings 41. As the stapling arm 30 and actuating lever 61 are rocked about the pivot 37 the casing section 4 is rocked about its pivot 5 by the engagement of its roller 100 with the cam 68 on the lever 61. The engagement of the top of the wings 41 on the stapling arm 30 with the stop 76 limits the return movement of the arm, while the engagement of the rearward and bottom portion of the casing section 4 with the flange 8 on the casing section 3 limits its movement as indicated in Fig. 1. At the end of the upward movement of the casing section 4, the roller 98 moves out of engagement with the arm 93 to release the work-support 91. The leaf-spring 95 then rocks the forward end of the work-support 91 into its inoperative position within the recess or slot 19 in the anvil 17. The staple-driver 60 being raised above the magazine-core 35 permits a staple S to be advanced into the throat 53 to a position beneath the driver by the action of the pusher 78. The pusher 78 is adapted to advance the

staples in the magazine until they are completely exhausted, the pusher moving forwardly with the ear 83 passing between the spaced sides of the staple-retainer 85 until it engages the 5 driver 60, at which time the last staple in the magazine is positioned in the throat. A staple S having been advanced to a position beneath the end of the driver 60 the implement is then ready for another staple-applying operation which may 10 be performed in the same manner as above explained.

After the supply of staples S in the magazine has become exhausted, or if for any other reason it becomes necessary to open the end of the 15 stapling arm 30, the gate 46 is slid upwardly against the action of the spring 51 to disengage its notches 49 from the lugs 50 and then rocked on its pivot-pin 45. When the gate 46 is opened, as indicated in Fig. 13, the staple-driver 60 is 20 released at the front which permits the spring 88 to rock the staple-retainer 85 to engage its eccentrically curved edge 87 with any staples remaining in the magazine. The staples are thus prevented from being ejected from the magazine 25 by the staple-pusher 78 under the tension of the elastic cord 80.

When the supply of staples is completely exhausted and the gate 46 opened the staple-pusher 78 is prevented from movement beyond the end 30 of the stapling arm 30 by the engagement of its laterally-extending ears 84 with the rearward edges of the wings 41. A new supply of staples, preferably in the form of a stick, may be inserted in the magazine by sliding them onto the core 35 35 and under the curved end 87 of the staple-retainer 85 which yields to permit the staples to pass thereby. After a refill of staples has been inserted in the stapling or magazine arm 30 the gate 46 is closed which causes the staple-driver 60 to again engage the crossbar 90 of the staple-retainer 85 to rock it to its inoperative position illustrated in Fig. 7. The gate 46 is then resiliently held closed and latched in place by the spring 51 acting on its pivot-pin 45.

45 It will be observed from the foregoing that the present invention provides a novel construction and arrangement of elements in a stapling device for gripping and holding the work away from the anvil while the staples are driven therethrough. It will also be observed that the implement provides for bending the legs of the driven staple after it has been driven through the work to form a flat pin-stitch which may be readily removed without damage to the work. 50 It will still further be observed that the invention provides a compact, easily-operated implement which is positive and efficient in operation to perform its intended function.

55 While the device is herein described and illustrated as embodied in a preferred form of construction, it is to be understood that various modifications may be made in the structure and arrangement of its parts without departing from the spirit or scope of the invention. Therefore, without limiting myself in this respect, I claim:

1. In a device of the type indicated, fastener-applying mechanism, a relatively stationary anvil for clinching the fasteners in the work, a work-support independent of the anvil and normally positioned in spaced relation to the fastener-applying mechanism, said work-support being mounted on a fixed pivot for movement away from the anvil toward the fastener-applying mechanism to grip the work thereagainst and hold it suspended above the anvil, and means

for actuating the work-support to move it toward the fastener-applying mechanism.

2. In a device of the type indicated, fastener-applying means, an anvil for clinching the fasteners in the work, a work-support independent of the anvil, said work-support being mounted on a fixed pivot to adapt it to rock away from the anvil toward the fastener-applying means to grip the work against the latter and hold it in spaced relation to the anvil, and means for rocking the 10 work-support to grip and hold the work.

3. In a device of the type indicated, a stationary anvil, fastener-applying means movable toward and away from the anvil, a work-support independent of the anvil, said work-support being mounted on a fixed pivot to rock away from the anvil toward the fastener-applying means, and means engaging the work-support to rock it on its pivot toward the fastener-applying means to grip the work thereagainst and hold it suspended above the anvil.

4. In a device of the type indicated, a stationary anvil, fastener-applying mechanism movable toward and away from the anvil, means for operating the fastener-applying mechanism to apply the fasteners to the work, and a work-support independent of the anvil and mounted on a fixed pivot to adapt it to be rocked between the anvil and fastener-applying mechanism, said work-support being actuated by the means for operating the fastener-applying mechanism to rock it toward the latter to grip the work thereagainst and hold it suspended above the anvil.

5. In a device of the type indicated, a casing having an anvil thereon, fastener-applying means mounted in the casing for movement toward and away from the anvil to clinch a driven fastener, a work-support independent of the anvil and normally held in spaced relation to the fastener-applying means while being movable toward the latter to grip the work therebetween, and means operative to actuate the work-support to grip the work and to then actuate the fastener-applying means to apply a fastener in succession.

6. In a device of the type indicated, a stationary anvil, fastener-applying means including a driver movable toward the anvil, a work-support independent of the anvil and normally positioned in spaced relation to the fastener-applying means, said work-support being mounted on a fixed pivot to adapt it to rock away from the anvil toward the fastener-applying means to grip the work thereagainst and hold it suspended above the anvil, and operating means for first rocking the work-support toward the fastener-applying means to grip the work and thereafter apply a fastener, said operating means then acting to move the fastener-applying means and work-support toward the anvil to clinch the legs of the fastener to form a stitch.

7. In a fastener-applying implement, the combination of a compressible casing comprising complementary sections pivoted together and arranged to telescope one within the other, fastener-applying means enclosed within the casing, a work-support mounted on the casing and movable toward the fastener-applying means to grip the work therebetween, and means operative by compressing the casing to actuate the work-support to grip the work and operate the fastener-applying means.

8. In a device of the type indicated, the combination of a relatively stationary anvil, fastener-applying means, a pivoted lever for actuating the fastener-applying means, a work-support inde-

pendent of the anvil and normally spaced from the fastener-applying means, said work-support being movable toward the fastener-applying means to grip the work therebetween, manually-operable means overlying the actuating lever and work-support, and means on said manually-operable means for operating the work-support and the actuating lever for the fastener-applying means in succession, said fastener-applying means being movable toward the anvil to clinch a driven fastener.

9. In a device of the type indicated, the combination of fastener-applying means, a pivoted lever for actuating the fastener-applying means, a work-support pivoted intermediate its ends and having an arm at one end for rocking its opposite end toward the fastener-applying means to grip the work therebetween, manually-operable means movable with respect to the lever and arm on the work-support, and rollers on the manually-operable means, one of said rollers engaging the arm to operate the work-support and the other roller engaging the lever to operate the fastener-applying means.

10. In a machine of the type indicated, a frame, an anvil on the frame, fastener-applying means on the frame movable toward and away from the anvil, a work-support normally held in spaced relation to the fastener-applying means while movable toward the latter to grip the work therebetween, and a common means for successively operating the work-support and fastener-applying means to first move the work-support toward the fastener-applying means to grip the work and hold it suspended above the anvil and then apply a fastener, said operating means thereafter acting to move the fastener-applying means toward the anvil to bend the legs of the fastener to form a stitch.

11. In a machine of the type indicated, a frame, an anvil on the frame having means for bending the legs of a staple to form a stitch, a stapling arm pivotally mounted at one end on the frame to adapt its opposite end for movement toward the anvil, staple-driving means on the arm, a work-support pivotally mounted on the frame for movement toward the stapling arm to grip the work thereagainst, and means operative to actuate the work-support to move it toward the staple-driving means and to thereafter actuate the staple-driving means to drive a staple through the work while it is held away from the anvil, said stapling arm being rocked about its pivot to cause the legs of the staple to be bent on the anvil.

12. In a machine of the type indicated, a frame, an anvil on the frame having means for bending the legs of a staple to form a stitch, a stapling arm pivoted to the frame, a staple-driver carried by the arm, a resilient work-support pivotally mounted intermediate its ends on the frame, and an operating member engageable with one end of the work-support to rock its opposite end toward the stapling arm to grip and hold the work suspended and connected to thereafter operate the staple-driver to drive a staple through the work, said work-support being adapted to yield after the staple has been driven to permit the stapling arm to be rocked to engage the legs of the staple with the anvil and cause them to be bent.

13. In a fastener-applying implement, the combination of a compressible casing comprising two complementary sections arranged to move one with respect to the other, an anvil on the casing,

fastener-applying means mounted in the casing for movement toward the anvil, a work-support mounted in the casing for movement toward the fastener-applying means to grip the work and hold it spaced from the anvil, and means operative by compressing the casing sections to actuate the work-support to move it toward the fastener-applying means to grip the work and to thereafter operate the fastener-applying means to apply a fastener to the work, said fastener-applying means and work-support being movable toward the anvil after the fastener is driven to bend its legs to form a stitch.

14. In a device of the type indicated, a frame, an anvil on the frame having a recess, means on said anvil for bending the legs of a staple, staple-applying means mounted on said frame for movement toward the anvil, a work-support mounted on the frame and normally positioned in the recess in the anvil, and manually-operative means for moving the work-support toward the staple-applying means to grip and hold the work away from the anvil and operating the staple-applying means to apply a staple, said operating means thereafter acting to rock the stapling arm toward the anvil to bend the legs of the staple.

15. In a device of the type indicated, a frame, a stapling arm pivotally mounted on the frame, a staple-driver on the arm, an actuating lever pivoted to the arm at one end and connected to the staple-driver at its opposite end, said lever having a cam-face intermediate its ends, a work-support pivotally mounted on the frame and having an arm at one end, and a manually-operative lever pivotally connected to the frame and having rollers for engaging the cam on the lever and the arm on the work-support to actuate said lever and support.

16. In a fastener-applying implement, the combination of a compressible casing comprising complementary sections pivoted together and arranged to telescope one within the other, staple-applying means mounted in the casing, a work-support in the casing pivotally mounted intermediate its ends, one of the ends of said work-support having an arcuately-shaped arm with its extremity curved reversely with respect to its arcuate portion, a roller carried by one of the casing sections for engaging the arm on the work-support to rock the latter, and a second roller engaging the staple-applying means to actuate the latter.

17. In a fastener-applying implement, a frame, staple-applying means pivotally mounted on the frame, a work-support pivotally mounted on the frame on an axis common to the pivotal axis of the staple-applying means for movement toward the latter, and a lever on the frame operative to move the work-support and staple-applying means toward each other and to then actuate the latter to apply a staple to the work.

18. In a fastener-applying implement, a magazine arm comprising an outer channel-shaped casing, a core for staples nested within the outer casing, the side walls of the outer casing being extended beyond the end of the inner core and bent inwardly to position their ends in spaced-apart parallel planes, and a pivoted gate enclosing the end of the magazine arm and cooperating with the end of the inner core member and the ends of the inwardly-bent side walls to form a throat, said ends of the inwardly-bent side walls forming lateral guides for the legs of a staple.

19. In a staple-applying implement, a magazine, a gate pivotally mounted on the magazine for opening or closing its end, a staple-pusher for feeding the staples along the magazine, and a self-energizing staple-retainer pivotally mounted above the magazine and having an arcuate edge so arranged as to adapt it to engage the staples in the magazine, said staple-retainer being pivoted eccentrically of its arcuate edge whereby the engagement of said edge with the staples will tend to rock the staple-retainer to wedge it between its pivot and the staples, said gate acting when closed to rock the staple-retainer to inoperative position with its arcuate edge free from engagement with the staples.

JOHN F. CAVANAGH.
